(57) CLAIM

The ornamental design for an eraser, as shown and described.

DESCRIPTION

FIG. 1 is a front elevation view of an eraser showing my new design;

FIG. 2 is a rear elevation view thereof;

FIG. 3 is a right side elevation view thereof, with the left side elevation view being a mirror image of the right side elevation view;

FIG. 4 is a top plan view thereof;

FIG. 5 is a bottom plan view thereof;

FIG. 6 is an enlarged top plan view thereof;

FIG. 7 is an enlarged bottom plan view thereof; and,

FIG. 8 is an upper front right perspective view thereof.

The broken lines at the upper end of the eraser shown in FIGS. 4, 6, and 8 illustrate environmental matter that forms no part of the claimed design.
